UNITED STATES PATENT OFFICE.

JOHN F. OHMER, OF DAYTON, OHIO, ASSIGNOR TO OHMER FARE REGISTER COMPANY,
OF ROCHESTER, NEW YORK.

FARE-REGISTER.

937,220.

Specification of Letters Patent. Patented Oct. 19, 1909.

Original application filed January 11, 1904, Serial No. 188,430. Divided and this application filed January 28, 1907. Serial No. 354,473.

To all whom it may concern:

Be it known that I, JOHN F. OHMER, a citizen of the United States, residing at Dayton, in the county of Montgomery and 5 State of Ohio, have invented certain new and useful Improvements in Fare-Registers; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to new and useful improvements in fare registers, and the application is divided from my pending application filed Jan. 11, 1904, Serial No. 188,430.

The invention comprises a plurality of 20 specific fare printing counters, upon which are registrable the different classes of fares, a grand trip total printing counter upon which is registrable the sum total of all the fares registered on the specific fare printing 25 counters for each trip, a passenger indicating counter, and reciprocating mechanism including a transverse oscillating bar interposed between the specific fare printing counters, the grand total trip printing counter, and the fare indicating counter, whereby, 30 in each operation of a specific fare printing counter, the reciprocating mechanism will concurrently operate the grand total trip printing counter and the trip indicating counter.

35 Preceding a detail description of the invention, reference is made to the accompanying drawings, of which—

Figure 1, is a front elevation of the mechanism removed from its casing. Fig. 2, is a vertical section on the line α — α of Fig. 1. Fig. 3, is a detached view of the reciprocating slide of the grand total printing counter. Fig. 4, is an illustration of the printed statement which is taken from the machine.

In a detail description of the invention, similar reference characters indicate corresponding parts.

The supporting frame 1 for the various 50 parts is of suitable design and construction. In the upper portion thereof is supported the shaft 6 of the passenger indicating counter comprising three wheels 2 which are loose upon the shaft 6. Each of said wheels has

fixed to its outer side a ratchet wheel 4 55 adapted to engage each with a ratchet pawl 5 mounted upon a horizontal shaft 3 which has an oscillating movement in arms 7 which are pivoted on the shaft 6. One of the arms 7 is pivotally connected by means of a depending link 8 to a transverse reciprocating bar 9 which lies across the machine and has its ends journaled in the sides of the frame. Below this reciprocating bar 9 there is slidably mounted a series of vertically-reciprocating members 10, one of which co-operates with each of the specific fare counters 11, there being shown four groups of specific fare printing counters 11. Upon the actuation of any one of these reciprocating members 10, the transverse reciprocating bar 9 will be elevated, and through the connecting link 8, the pawl shaft 3 will be actuated to cause the pawls one at a time to engage the respective ratchet wheels 4 of the indicating 75 counters 2.

Arranged upon the shaft upon which the specific fare printing counters 11 are mounted, is a grand total trip printing counter 12 which is permanently connected to the transverse reciprocating bar 9 through a vertically-reciprocating slide 13 so that each actuation of the transverse reciprocating bar 9 will also operate the grand total trip printing counter.

The indicating counters 2, in a sense, are total counters in that they are operated each time one of the specific fare printing counters is operated, but these indicating counters are set to zero at the beginning of each trip; 90 the grand total printing counters are continuous in their operations and are not set to zero. The reciprocating members 10 each actuate a pawl-carrying arm 14, one of which is associated with each group of specific fare 95 counters; these pawl-carrying arms 14 are pivotally mounted upon the shaft of the actuating wheels of the specific fare counters, and each of said pawl-carrying arms supports a pawl 15 which engages the ratchet 100 wheel 16 attached to a side of the primary actuating wheel of each group of specific fare counters, as fully described and illustrated in former patent No. 715,129 of Dec. 2, 1902, granted to John F. Ohmer and Hiram Tyler. Each of the reciprocating members 10 has a rearwardly projected lug 17 105 with which the selective and operating mech-

anism (not shown) is designed to engage in the operations of any one of said reciprocating members.

The printing mechanism associated with

- 5 the present invention is fully described and illustrated in my former Letters Patent No. 715,129 and briefly referred to consists of a roll of paper 18 which is mounted in hinged side plates 19 which are pivotally connected
- 10 in the lower end of the frame-work; the paper from this roll passes through feed rollers 21 and 22 below the specific fare printing counters and the grand total trip printing counter; below said paper is a platen 20
- 15 which is actuated by a transverse eccentric bar 23 journaled in said side plate and which is turned to elevate the platen and the paper against said printing counters, by a key (not shown) in the usual manner, and as illustrated and described more fully in the patent hereinbefore referred to. The inking roller 24 journaled in the side plates applies ink to the printing counters preparatory to the operation of printing the statements.
- 25 The passenger indicator counters 2 are set to zero through the movement of the hand wheel 25 which has a gear wheel 26 on its shaft, said gear wheel engaging a gear wheel 27 on the shaft 6 of said counters. The statement shown in Fig. 4, contains the totals of each specific fare counter, and the total of all the fares.

I claim:

- 35 1. In a fare register, a counter for printing the total number of fares for each trip, an indicator comprising a series of counter wheels corresponding to the counter for printing the total number of fares for each trip, and reciprocating connections having
- 40 among them an oscillating lift bar to cause said total trip printing counter and said indicator to move in unison, and means consisting of a series of individual operating slides for actuating said reciprocating mechanism to simultaneously operate said indicator and said trip total printing counter.
- 45 2. In a fare register, a total printing counter to print the total fares collected for each trip, an indicator comprising a series
- 50 of wheels corresponding to said total printing counter and adapted to indicate the fares collected or passengers carried on each trip, a transversely-disposed reciprocating bar, oppositely-disposed reciprocating connections between said bar and said indicator and said total trip printing counter, respectively, whereby said counter and said indicator are moved in unison, and means for actuating said reciprocating bar, comprising

a series of individual members similarly 60 engaging the reciprocating bar when vertically moved.

3. In a fare register, a counter for printing the total number of fares for each trip, an indicator comprising wheels correspond- 65 ing to said printing counter, an oscillating reciprocating member intermediate said indicator and said printing counter, reciprocating connections between said oscillating reciprocating member and said indicator and 70 said counter respectively, and a series of individual reciprocating members coöperating with the specific fare counters and adapted to actuate said intermediate oscillating reciprocating member uniformly to impart 75 uniform movements to said indicator and said printing counter.

4. In a fare register, a printing counter for printing the total fares for each trip, a fare or passenger indicator comprising a 80 group of wheels, a transverse pivotal reciprocating member, a depending connection between said indicator wheels and said transverse pivotal reciprocating member, an upright connection between said printing 85 counter and said transverse pivotal reciprocating member, and a series of vertically-reciprocating slides coöperating with the specific fare counters and adapted to uniformly 90 actuate said transverse pivotal reciprocating member to move in unison the indicator and the printing counter.

5. In a fare register, a plurality of specific fare printing counters, a grand total trip printing counter to print the total fares 95 per trip as per the specific fare printing counters, a fare or passenger indicator comprising wheels corresponding to said total trip printing counter, a transverse reciprocating member interposed between the specific fare printing counters, the total trip printing counter and the indicator, reciprocable slides between the indicator and the total trip printing counter adapted to move said indicator and said counter in unison 100 upon the registration of each fare on the specific fare counters, and an individual operating member for each specific fare counter adapted to actuate the transverse reciprocating member upon the registration of each 110 fare on a specific counter.

In testimony whereof I affix my signature, in presence of two witnesses.

JOHN F. OHMER.
